The ornamental design of a removable paint roller splatter shield, as shown and described.

DESCRIPTION

FIG. 1 is a perspective view of a removable paint roller splatter shield showing my new design, and illustrating a paint roller in phantom;

FIG. 2 is an end view thereof;

FIG. 3 is an end view of the opposite end thereof;

FIG. 4 is a top view thereof;

FIG. 5 is a side view thereof, the opposite side view being a mirror image; and,

FIG. 6 is a bottom view thereof.

The broken line showing a paint roller is for illustrative purposes only and forms no part of the claimed design.
